UNITED STATES PATENT OFFICE.

JOSEPH B. MOCKRIDGE, OF NEW YORK, N. Y., ASSIGNOR OF ONE-HALF TO
JULIUS G. HOCKE, OF BAYONNE, NEW JERSEY.

POULTRY-CAR.

SPECIFICATION forming part of Letters Patent No. 689,210, dated December 17, 1901.

Application filed November 30, 1900. Serial No. 38,113. (No model.)

To all whom it may concern:

Be it known that I, JOSEPH B. MOCKRIDGE, a citizen of the United States, residing in the borough of Manhattan, city, county, and State 5 of New York, have invented certain new and useful Improvements in Poultry-Cars, of which the following is a specification.

My invention relates to cars for shipping live poultry.

10 I will describe a poultry-car embodying my invention and then point out the novel features thereof in the claims.

In the accompanying drawings, Figure 1 is a cross-sectional view of the body portion of 15 a poultry-car embodying my invention. Fig. 2 is a view, partly in horizontal section and partly in top plan, of a poultry-car embodying my invention. Fig. 3 is a detail side elevational view of a twin section in which poultry is confined. Fig. 4 is a detail longitudinal sectional view, partly in side elevation, of a modification of my invention.

Similar letters of reference designate corresponding parts throughout the drawings.

20 A represents the body of a car, which is suitably mounted on wheeled trucks. (Not shown.) The sides *a* of the car are preferably provided with sliding doors *a'*. I also provide sliding or hinged sashes 25 *a²* in the sides of the car for the purpose of admitting light and air to the interior of the car. The ends of the car may be provided with a single and centrally-arranged door or with a single or a number of doors so arranged 30 as that the car may be completely opened at its ends to permit of its being emptied and refilled. This latter arrangement will be hereinafter described in connection with a modification of my invention. The bottom 35 40 of the car is provided with a number of openings *a³*, through which droppings from the poultry confined in the sections within the car pass out of the car. The top of the car is provided with a number of trap-doors *a⁴*,

45 and a grating *a⁵* is placed beneath each trap-door *a⁴*. The purpose of these trap-doors is to provide for a vertical circulation of air within the car. Air may pass through the trap-door openings and out of the car through 50 the openings *a³*, or the passage of air may be in a direction reverse to that just described.

B represents a number of poultry-sections provided within the car. Each section B comprises a number of compartments *b*, each compartment being of such a size as to confine a fowl and prevent the fowl from turning in the compartment. The sections B are alike as to construction and complement of parts. The following description of one section, therefore, will apply equally to all. 55 Angle and T iron is preferably used in constructing the framework, which comprises base-pieces *c*, upright pieces *c'*, and top pieces *b'*. These several parts are suitably secured together. The framework preferably has 60 more breadth than width and more height than breadth. Intermediate of the top and base or bottom of the framework are cross-pieces *c²*, which may serve as braces for the framework and upon which the floorings of 65 the compartments are supported. The floorings may be of wood or any other desired and suitable material. The spaces between the floorings are divided by suitable vertical partitions *c⁴* to form the single compartments 70 75 *b*. With this arrangement it will be seen that in a section there are horizontal tiers of compartments *b*, and when the horizontal tiers are superimposed vertical tiers of compartments are formed. Extending along 80 each horizontal tier and at right angles to the partitions is a partition-wall or closure *c⁵*, having a number of openings *c⁶*, one for each compartment *b*, through which the fowls in that horizontal tier may pass their heads. 85 Also extending along each horizontal tier and in front of the wall *c⁵* is a platform *c⁸*, supported by the cross-pieces *c³*, which may be extended for this purpose.

c' represents a trough which is supported 90 by the platform *c⁸*.

Opposite the wall *c⁵* and at the end of the compartment is a device D, which prevents droppings from the fowls above reaching the fowls or compartments for which the device 95 D is provided. This device is here shown as an apron which has a hinged connection with the framework, brackets *d* being provided to receive the pintle ends of the apron. Each horizontal tier of compartments is provided 100 with a hinged apron for the purpose above stated. The lower or free edge of each apron

is held away from the framework to permit droppings from the fowls to pass out of the compartments. With the lower edges of the aprons held away from the compartments a series of inclined surfaces are provided, each of which serves to deflect droppings from the fowls above away from its compartment and the compartments beneath and through the openings a^3 in the car-floor. The aprons D also serve as doors for the compartments. When the aprons are raised to horizontal position, as shown to the right of Fig. 3, the compartments may be emptied or filled with fowls. Any desired means may be employed for raising or lowering the aprons D—as, for example, the following: The upper or topmost apron is provided with a pair of links d^2 , which are connected to the ends of levers d^3 , fulcrumed or hinged to two of the top pieces b' . Fulerumed to one of the top pieces b' is a hand-lever d^4 , which is provided intermediate of its ends with a link d^5 , which link d^5 connects the lever d^4 with a link d^2 and a lever d^3 . When the hand-lever is swung outwardly on its fulcrum, all the aprons are raised or moved to a horizontal position, as shown to the right in Fig. 3. The aprons may be held in this position by means of a link d^6 , secured at one end to the pin or other device connecting the link d^2 and lever d^3 and adapted to have its other end engage with one of a number of openings d^7 in the hand-lever d^5 .

b^2 represents rollers or pulleys journaled in brackets b^3 , which brackets are secured to the section at its upper end—for example, to the top pieces b' . These rollers or pulleys b^2 travel on tracks b^4 , which are suitably supported from the top of the car. Rollers or other devices b^5 are provided for the base of the section, which devices b^5 travel on tracks provided on the car-floor.

For convenience in manufacturing and for other reasons I preferably construct the sections in pairs. With this arrangement the top pieces b' and base or bottom pieces at the short sides of each section in each pair are common to both sections of that pair. In other words, they extend without a break from one section to the other. The cross-pieces c^3 , parallel with the side top and base pieces, are also common to both sections of each pair. It is on those portions of the cross-pieces c^3 which are outside of the sections of each pair that the platform c^8 and troughs c^7 are supported. The heads of the fowls confined in the sections of each pair are toward each other, so that a single trough will suffice for the opposite horizontal tiers of compartments. In adjacent pairs the adjacent sections are near the openings a^3 in the car-floor.

In order that the pairs of sections may be relatively fixed in the car, each pair is provided with stops b^7 , here shown as consisting of extensions of the side top pieces b' and corresponding base-pieces c . The stops b^7

of adjacent pairs abut against each other. For convenience the pairs of sections are arranged within the car in four series, which arrangement permits of a passage transversely of the car as well as a passage longitudinally. If, therefore, the first and last pair of sections in each series are locked or otherwise prevented from movement of the tracks, the stops b^7 will prevent any movement of the intermediate sections. The pairs of sections, however, may be independently secured from movement.

In Fig. 4 I have shown the tracks b^4 as extending to the ends of the car. This is for the purpose of enabling the poultry-sections to be run out of the car at its ends onto overhead tracks G , located in a ware or other house. Instead of overhead tracks rails or other devices secured to the floor of the ware-house may be used. This arrangement is advantageous in that the car may be quickly emptied of filled sections and refilled with empty sections. The filled sections removed from the car may be emptied as desired.

Having thus described my invention, what I claim as new is—

1. A poultry-carrier comprising a plurality of compartments arranged in vertical tiers, and means provided for each compartment which prevent droppings from reaching the compartment or compartments beneath it.

2. A poultry-carrier comprising a plurality of compartments arranged in vertical tiers, and each of such a size to confine a single fowl so as to prevent turning, and means provided for each compartment which prevent droppings from reaching the compartment or compartments beneath it.

3. The combination of a portable housing having openings in its floor, poultry-carrying sections within said housing and adjacent said openings, each of said sections comprising a plurality of compartments arranged in vertical tiers and each of a size to confine a single fowl so as to prevent turning, and means provided for each compartment which deflects droppings from the fowl within it through the openings in the floor of said housing.

4. A poultry-carrier comprising a plurality of compartments arranged in horizontal and vertical tiers, and an apron provided for each horizontal tier of compartments which prevents droppings from the fowls in its horizontal tier of compartments from reaching any compartment or compartments beneath it.

5. A poultry-carrier comprising a plurality of compartments arranged in vertical tiers, and an apron provided for each compartment to prevent droppings from the fowl in its compartment reaching the fowls or compartments beneath it.

6. A poultry-carrier comprising a plurality of compartments arranged in horizontal and vertical tiers, and each adapted to confine a fowl, an apron provided for each horizontal

tier which prevents droppings of the fowls in its horizontal tier from reaching the fowls or compartments beneath it, and means for moving said aprons from one position to another.

5 7. A poultry-carrier comprising a plurality of compartments arranged in vertical and horizontal tiers and in two sections, which sections are connected together to form a pair of sections, and a trough supported between adjacent horizontal tiers of the sections.

8. A poultry-carrier comprising a plurality of compartments each adapted to confine a fowl, arranged in vertical and horizontal tiers and in two sections, which sections are coupled together, a trough supported between opposite horizontal tiers of the two sections, and an apron provided for each compartment which prevents droppings from the fowls in

its compartment reaching the fowls and compartments beneath it.

9. A poultry-carrier comprising a plurality of compartments arranged in vertical tiers and each of a size to confine a single fowl, a hinged apron for each of said compartments which deflects droppings from the fowl confined in its compartment from the fowls and compartments beneath it, and means connected with said aprons for moving them on their hinges.

In testimony whereof I have signed my name to this specification in the presence of two subscribing witnesses.

JOSEPH B. MOCKRIDGE.
